UNITED STATES PATENT OFFICE.

CHARLES B. BRAUNSTEIN, OF CINCINNATI, OHIO.

DESIGN FOR AN EMBLEM OR SIMILAR ARTICLE.

No. 39,587.

Specification for Design.

Patented Sept. 29, 1908.

Application filed August 3, 1908. Serial No. 446,823. Term of patent 3½ years.

To all whom it may concern:

Be it known that I, CHARLES B. BRAUNSTEIN, a citizen of the United States, residing at Cincinnati, in the county of Hamilton and State of Ohio, have invented a new, original, and ornamental Design for Emblems or Similar Articles, of which the following is a specification, reference being had to the accompanying drawing, forming part thereof.

The figure is a front elevation of the emblem, showing my new design.

I claim:

The ornamental design for an emblem, or similar article, as shown.

CHARLES B. BRAUNSTEIN.
